US00D814511S

(12) United States Design Patent (10) Patent No.: US D814,511 S
(45) Date of Patent:  Apr. 3, 2018

(54) DISPLAY SCREEN WITH ICON

- (71) Applicant: ROCKWELL AUTOMATION TECHNOLOGIES, INC., Mayfield Heights, OH (US)
- (72) Inventors: Benjamin Henderson, Chardon, OH (US); Matthew R. Ericsson, Lyndhurst, OH (US); Ashish Anand, Mayfield Heights, OH (US)
- (73) Assignee: Rockwell Automation Technologies, Inc., Mayfield Heights, OH (US)
- () Term: 15 Years
- (21) Appl. No.: 29/579,292
- (22) Filed: Sep. 29, 2016

Related U.S. Application Data

- (62) Division of application No. 29/512,460, filed on Dec. 18, 2014, now abandoned.
- (51) LOC (11) Cl. 14-04
- (52) U.S. Cl.
USPC D14/489
- (58) Field of Classification Search
USPC D14/485-495
